CAN PUNCTURING TOOL

John Swanson, Hudson, Ohio

Application April 27, 1944, Serial No. 533,024

2 Claims. (Cl. 30—16)

This invention relates to a punch especially adapted for making openings in cans and like containers to be employed for venting the can and the pouring of the contents therefrom.

The primary object of the invention is the provision of a tool of the above stated character which will be extremely easy to handle and may be quickly applied over the end of a can and includes a pair of spaced penetrating elements which may be easily forced through an end wall of the can by pressure applied on the handle of the device thereby rupturing the can at different places, providing in the can the vent and pouring openings.

Another object of this invention is the provision of means for automatically withdrawing the puncturing elements from the can as soon as the pressure is released on the handle of the device, permitting the device to be conveniently removed from the can so that the can will become vented and the contents poured therefrom as desired.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a vertical sectional view illustrating a punch constructed in accordance with my invention and showing the device applied to one end of a can.

Figure 2 is a bottom plan view illustrating the device.

Figure 3 is a sectional view taken on the line 3—3 of Figure 1.

Referring in detail to the drawing, the numeral 5 indicates an annular body, one end of which is closed by an end wall 6 and the opposite end of the annular body is beveled, as shown at 7, to flare said end of the body so that it may be readily inserted over the end of a can 8, as shown in Figure 1. The end wall 6 of the body is provided with spaced openings to receive screw threaded shanks 9 of puncturing elements 10. Nuts 11 are threaded on the shanks after passing through the openings of the wall 6 providing a construction which will permit the penetrating elements to be easily removed from the body should it be desired to sharpen the penetrating elements or replace them by others.

It is preferable that the openings for the pene-

trating elements be located close to the annular wall of the body arranging the penetrating elements a sufficient distance apart so that when they rupture the end wall of the can they will provide openings therein located adjacent the vertical walls of the can. One of the openings may be employed for pouring the contents of the can while the other opening admits atmospheric pressure so that the contents will flow freely.

10 A block of material 12 is detachably secured to the wall 6 of the body and is shaped to provide a hand grip. Screws or like fasteners 13 are employed for detachably securing the block of material to the body.

15 The block of material has formed therein a recess 14 of different diameters and is adapted to align with an opening 15 formed in the wall 6 of the body. The smallest diameter of the recess 14 forms a seat for one end of a coil spring 16, the other end of the coil spring bearing against a closed end 17 of a sleeve 18 slidably through the opening 15 and in the larger portion of the recess 14. The open end of the sleeve is flanged, as shown at 19, acting as stops for 20 preventing the sleeve from being forced entirely out of the recess 14 by the action of the spring when the device is removed from a can. The recess having the different diameters as before specified provides an internal shoulder 20 acting as a stop to be abutted by the flange 19 for limiting the inward movement of the sleeve. The sleeve may move inwardly of the recess 14 sufficient to permit the penetrating elements to pass through the end wall of the can until the end wall 6 of the body comes in contact with the can. As soon as pressure is released from the hand-grip the spring acts to withdraw the penetrating elements from the can by moving the end wall 6 away from the end wall of the can. The device in this position as shown in Figure 1 is ready to be removed from the can or to receive pressure for driving the penetrating elements through the end wall of the can.

45 While I have shown and described the preferred embodiment of my invention, it will be understood that minor changes in construction, combination and arrangement of parts may be made without departing from the spirit and scope of the invention as claimed.

50 Having thus described my invention, what I claim is:

1. In a container puncturing device, an annular body having one end fully open and provided with beveled edges to facilitate the placing of the annular body on one end of a container, an

end wall integral with the other end of the body, spaced puncturing elements removably seured to said end wall, a hand grip secured to said end wall, said end wall having an opening, said hand grip having a recess, and a spring influenced follower mounted for sliding movement in the recess and opening of the end wall to engage the container for normally positioning the puncturing elements out of the container.

2. In a container puncturing device, an annular body having one end fully open and provided with beveled edges to facilitate the placing of the annular body on one end of a container, an end wall integral with the other end of the

body, spaced puncturing elements removably secured to said end wall, a hand grip secured to said end wall, said end wall having an opening, said hand grip having a recess, a sleeve slidably mounted in the recess and opening of the end wall of the body and having one end fully closed and its other end flanged to abut the end wall of the body for limiting the sliding movement of the sleeve in one direction, and a spring interposed between a wall of the recess of the hand grip and the closed end of the sleeve for urging the flanged end of the sleeve against the end wall of the body.

JOHN SWANSON.
